US0D1111541S

(12) **United States Design Patent** (10) **Patent No.:** **US D1,111,541 S**
(45) **Date of Patent:** **** Feb. 10, 2026**

(54) **SOAP DISH**

(71) Applicant: **Chun Ki Kim**, Seongnam-si (KR)

CA	210991	*	9/2023
CN	305480442	*	12/2019
GB	6195714	*	3/2022

(72) Inventor: **Chun Ki Kim**, Seongnam-si (KR)

(**) Term: **15 Years**

(21) Appl. No.: **35/522,584**

(22) Filed: **Aug. 21, 2024**

(80) **Hague Agreement Data**

Int. Filing Date: **Aug. 21, 2024**

Int. Reg. No.: **DM/240582**

Int. Reg. Date: **Aug. 21, 2024**

Int. Reg. Pub. Date: **Oct. 11, 2024**

(51) **LOC (15) Cl.** 23-08

(52) **U.S. Cl.**

USPC **D6/532**

(58) **Field of Classification Search**

USPC D6/532, 536, 537, 512, 524, 538, 539,
D6/540

CPC A47K 1/08; A47K 5/02
